UNITED STATES PATENT OFFICE.

CHARLES C. CHRISTENSEN AND ROBERT McCALPIN, OF CHICAGO, ILLINOIS.

INCINERATOR.

Application filed December 2, 1922. Serial No. 604,478.

To all whom it may concern:

Be it known that we, CHARLES C. CHRISTENSEN and ROBERT McCALPIN, citizens of the United States of America, and residents of Chicago, Cook County, Illinois, have invented a certain new and useful Improvement in Incinerators, of which the following is a specification.

Our invention relates to an improvement 10 in incinerators and particularly to an incinerator for burning refuse such as garbage.

An object of our invention is to provide an incinerator in which the refuse, such as garbage, will be entirely consumed without the 15 production of any odor or any smoke. By our invention the flame is projected downward upon the material in the fire-pot and thus the refuse is progressively dried and then burned, starting from the top; the liquid in the material draining downward to the bottom of the pot. In this way the liquid does not interfere in any way with the 20 efficient operation of the flame, and, furthermore, the burning can commence almost immediately without first necessitating the drying 25 of the entire mass of refuse.

A further object of our invention is to provide a container for the refuse which can be easily and quickly removed from the 30 enclosing housing for the purpose of loading.

These and other features and objects of our invention will be more readily understood by having reference to the accompanying drawings, in which we have illustrated 35 one embodiment of our invention.

In the drawings—

Figure 1 is a front elevation of an incinerator embodying the features of our invention;

Fig. 2 is a vertical sectional view of the 40 same;

Fig. 3 is a longitudinal sectional view; and

Fig. 4 is a detail sectional view showing a portion of the mounting for the fire-pot.

As illustrated, our incinerator comprises 45 essentially a fire-pot 5 mounted within an enclosing housing 6. This housing is preferably made with an auxiliary wall 7 passing around the rear and sides of the housing, 50 separated from the main wall by a dead air space 8. Likewise mounted below the top of the housing 6 is an auxiliary wall 9 separated from the top wall by the dead air space 10. A suitable hood 11 is mounted up- 55 on the top of the housing and passing through the top of the housing and upward

through the hood is the exhaust flue 12. This exhaust flue extends downward so that the lower end 13 of the same is located to one side of and below the upper edge 14 of the 60 fire-pot.

The fire-pot is mounted upon a grate 15 to the sides of which are secured rails 16. These rails are guided over rollers 17 mounted in suitable brackets 18 secured to the bottom of the housing. The roller 19 is likewise provided at the front end of the housing for engaging the upper surface of each of the rails. Carried by the brackets 20 (see Fig. 4) secured to the grate 15 there is 70 an ash pan 21. Likewise carried by the grate and extending upward therefrom is a front plate 22 which covers an opening in the front of the housing, which opening is provided for the purpose of enabling the 75 fire-pot being easily rolled out of the housing for the purpose of being re-charged. A handle 23 is secured to this front plate, and this plate is also provided with screened air-inlets 32, 33.

In order to consume the material in the fire-pot, a suitable burner 24 is provided. This burner is supplied with gas through the pipe 25 and projects the flame downward through the tube 26. The upper end of this 85 tube is provided with a conical end portion 27 into which air is drawn through openings 28 to thus create an efficient and hot flame. The burner can be ignited in any suitable way such as by a pilot 29. The sight-window 30 is preferably provided in the front 90 of the housing so that the progress of the combustion may be observed.

In operation the fire-pot is first withdrawn from the housing sufficiently to permit the loading of the fire-pot. Complete withdrawal of the fire-pot is prevented by reason of the projections 31 on the inner end of the rails striking the upper roller 19. After being loaded the fire-pot is shoved back into the housing and the flame then ignited. This flame is projected downward upon the material which, if garbage, is somewhat difficult to consume and must first be dried. The flame striking the upper surface of the refuse progressively dries and then ignites and burns the same. Any smoke which may arise in the initial drying must pass through the path of the flame and is thus consumed. A large quantity of oxygen is necessary in order to bring about complete combustion, and in our construction 105 110

this oxygen is provided by the air being drawn through the inlet opening 32 provided in the front plate 22 as well as from the smaller opening 33 provided below the 5 fire-pot. The air passing through the inlet opening 32 passes over the top of the fire-pot and thence downward into the material; while the air passing through the inlet opening 33 passes through the grate 15 and 10 thence upward through the material. The air is prevented from passing directly up the flue by means of the trough-shaped member 35 carried by the grate 15 and extending upwardly therefrom. By having the lower 15 end 13 of the exhaust flue 12 extend below the upper edge of the fire-pot, the air is prevented from passing directly across the top of the fire-pot as this construction forms a baffle so that the draught is broken suffi- 20 ciently to cause the air to be forced downward into the material and thus bring about a complete burning of the same. As the burning progresses the material is gradually dried and then burned, the liquid seeping 25 downward through the material and thus not interfering in any way with the efficient operation of the burner. The fire-pot is so formed that the flame reaches substantially all portions of the same and thus all the ma- 30 terial is effectively consumed and this is accomplished without the emission of any smoke, for, as before stated, any smoke which may arise from the material must pass through the path of the flame and is there 35 consumed.

While we have illustrated and described one particular embodiment of our invention, it will be understood that we do not wish to be limited to the exact construction shown 40 and described, but that various changes and modifications may be made without departing from the spirit and intent of our invention.

What we claim as our invention is:

45 1. In an incinerator, a container for refuse, a housing enclosing the top of said con-

tainer, a burner mounted above said container for projecting a flame downward on the refuse in said container in order to completely consume the refuse contained therein, an opening in the front of said housing for passing air over the top of said container downward into the material contained therein, and an exit flue extending upward through said housing the lower end of said flue terminating below and outside of the upper edge of said container. 50

2. In an incinerator, a container for refuse, a housing enclosing the top of said container, a burner mounted above said container for projecting a flame downward on the refuse in said container in order to completely consume the refuse contained therein, an opening in the front of said housing for passing air over the top of said container downward into the material contained therein, and an auxiliary opening in said housing for passing air upward through the bottom of said container and thence through 60 the material contained therein. 65

3. In an incinerator, a container for refuse, a housing enclosing the top of said container, a burner mounted above said container for projecting a flame downward on the refuse in said container in order to completely consume the refuse contained therein, an opening in the front of said housing for passing air over the top of said container downward into the material contained therein, an auxiliary 70 opening in said housing for passing air upward through the bottom of said container and thence through the material contained therein, an auxiliary 75 opening in said housing for passing air upward through the bottom of said container and thence through the material contained therein, and an exit flue extending upward through said housing the lower end of said flue terminating below and outside of the upper edge of said container. 80

Signed by us at Chicago, Illinois, this 22 85 day of November, 1922.

CHARLES C. CHRISTENSEN.
ROBERT McCALPIN.
